THROAT PLATE FOR SEWING MACHINES

Filed Oct. 3, 1927

UNITED STATES PATENT OFFICE

KARL MAIER, OF STUTTGART, GERMANY, ASSIGNOR TO UNION SPECIAL MASCHINEN-FABRIK, G. M. B. H.

THROAT PLATE FOR SEWING MACHINES

Application filed October 3, 1927, Serial No. 223,782, and in Germany October 25, 1926.

The invention relates to new and useful improvements in throat plates for sewing machines, and more particularly to the construction of a supporting tongue which projects into the needle slot and over which the 5 stitches may be formed.

An object of the invention is to provide a throat plate having means for detachably supporting a tongue which projects into the 10 needle slot, so that the tongue is held from lateral movement, and at the same time may be readily adjusted in an endwise direction and removed so that other tongues may be substituted therefor.

15 A further object of the invention is to provide a throat plate of the above type wherein the stitch tongue is in the form of a relatively thin plate having a laterally projecting portion by which it is secured and held in 20 vertical position, and wherein the throat plate is also provided with means for clamping the laterally projecting portion of the tongue and supporting the tongue at the sides thereof adjacent the needle slot.

25 A further object of the invention is to provide a throat plate of the above type having two tongues with a connecting bridge portion whereby said tongues are clamped to the throat plate.

30 These and other objects will in part be obvious and will in part be hereinafter more fully disclosed.

In the drawings—

35 Figure 1 is a perspective view of the throat plate embodying the invention;

Fig. 2 is a view partly in end elevation and partly in transverse section of the same;

Fig. 3 is a longitudinal sectional view through a portion of the throat plate;

40 Fig. 4 is a perspective view of the supporting tongues removed from the throat plate;

Fig. 5 is a perspective view of a modified form of supporting tongue, and

45 Fig. 6 is a view partly in end elevation and partly in section showing supporting tongues

of the type illustrated in Fig. 5 attached to the throat plate.

The invention is directed broadly to a throat plate for sewing machines, and more particularly to the construction of throat 50 plate which provides a supporting tongue or tongues over which the stitches may be formed. The throat plate has the usual needle slot, and directly in line with the needle slot and in front thereof, the throat plate is 55 provided with a groove in which the supporting tongue may be placed. The groove extends toward the front of the throat plate and joins the laterally extending recessed portion. The supporting tongue is in the form of a thin 60 metal plate which may be placed in the groove, and the plate has a laterally extending portion which lies in the recess. A clamping block is placed on the laterally extending portion in the recess, and serves to clamp the 65 tongue to the throat plate. When two stitch tongues are used, they may be provided with projecting portions which face each other, and a single clamping block used for both 70 projections. These projecting portions may be joined, thus forming an integral connecting bridge between the tongues. In this latter case, the bridge is formed with a slot 75 through which the clamping screw for the block passes, and this slot is elongated so as to permit the tongues to be adjusted in an endwise direction.

Referring more in detail to the drawings, the throat plate is indicated at *a* and is provided with the usual feed slots *b* and *c*. The 80 throat plate is also provided with the usual needle slots *d*. In the present embodiment of the invention there are two needle slots. The throat plate is secured to the cloth plate of the machine by screws passing through the 85 usual openings *e*. When there are two needle slots, then two supporting tongues are used, and these are indicated in the drawings at *f*. In the form of the invention illustrated in Figures 1 to 4, inclusive, the two tongues 90

f, f are connected by a bridging portion *g*. This bridging portion *g* is formed integral with the tongues, and projects laterally from the main body portion of the tongues. Each 5 tongue is in the form of a relatively thin metal plate. The forward end *l* extends into the needle slot, and is tapered on the under face thereof, so that the stitches when they are formed about the ends of the tongues, will 10 slide off from the tongues as the fabric is fed across the throat plate. The throat plate is provided with grooves in which these tongues are located, and these grooves form supporting portions *p, p* along each side of 15 the respective tongues adjacent the forward ends thereof. The grooves are in line with the needle slots and parallel with the line of feed. The grooves extend into the connecting recess portion *h*. The groove adjacent 20 the needle slot extends all the way through the throat plate, and the tongue is extended downwardly as indicated at *m*, so as to give a relatively wide support to the tongue adjacent the needle slot. This supporting of 25 the tongue at the sides thereof, prevents the tongue from lateral movement or tilting movement due to the pulling of the threads on the tongue. The bridge portion *g* lies in the recess *h*. A block *i* is placed on top of 30 the bridge portion, and a screw *k* passes through the block and is threaded into the throat plate. This screw *k* fills the space between the body portions *n, n* of the tongues, and thus it is that the tongues are substantially supported against lateral movement or 35 tilting throughout their entire length. By loosening the screw *k* and releasing the block, the tongues may be adjusted in an endwise direction, and then clamped in any set position. By removing the block, the tongues 40 may be readily removed from the throat plate and other tongues substituted therefor.

As shown in the drawings, these tongues are of such a width as to project above the 45 surface of the throat plate. This is for the purpose of forming a rib on the fabric which is being stitched. The tongues may be constructed so as to project in the manner shown, or may be made flush with the throat plate, as 50 they are desired. The above construction also provides means whereby the tongues may be quickly taken out when defective stitch formation occurs, and ground so as to remove any ridges forming thereon, and then again 55 easily inserted for use.

In Figures 5 and 6 of the drawings, I have shown a slightly modified form of the invention, in that the tongues are separately constructed. The tongues are similar to those 60 described above, except for the connecting bridge portion *g*. Instead of having the single integral bridge portion, each tongue is provided with lateral projections *r*. These lateral projections *r* face each other and are 65 of such width that when the tongues are in

place, they may be clamped by the block *i*, and the shank of the screw lies between the projecting portions *r*. By the above construction, it will be apparent that the tongues may be independently adjusted in a longitudinal direction. Also one tongue may be removed and another substituted therefor, or one tongue entirely removed from the machine and only one tongue used.

While I have shown and described in detail the use of two tongues, it will be understood that a single tongue may be used such as shown, for example, in Figures 5 and 6, and with all of the advantages which have been described above.

It is obvious that minor changes in the details of construction may be made without departing from the spirit of the invention as set forth in the appended claims.

Having thus described the invention, what I claim as new and desire to secure by Letters-Patent, is—

1. A throat plate for sewing machines having a needle slot, a groove in line with said slot, a relatively thin plate fitting in said groove and having a portion projecting into said needle slot over which the stitches may be formed, said plate projecting above the surface of the throat plate, and means for detachably securing the plate in said groove.

2. A throat plate for sewing machines having a needle slot and a groove in line with said slot, a supporting tongue fitting in said groove and projecting into said needle slot, said tongue having an integral laterally projecting shank portion at the outer end thereof extending into a recess formed in the throat plate, said tongue projecting above the surface of the throat plate, and a clamping block adapted to engage said shank and clamp the tongue to the throat plate.

3. A throat plate for sewing machines having a pair of needle slots, a groove in line with each needle slot, a supporting tongue located in each groove, a connecting shank portion joining said tongues at their lower edges and extending into a recess formed in the throat plate, said tongues projecting into said needle slots, and means disposed in said recess for engaging said connecting shank portion for clamping the tongues in said slots.

4. A throat plate for sewing machines having a pair of needle slots, a groove in line with each slot and a recess into which said groove extends, a supporting tongue located in each groove and extending into a respective needle slot, a shank portion connecting the lower edges of said tongues and located in said recess, a block adapted to rest on said shank portion and fill said recess, and a clamping screw for said block, said shank having an elongated slot formed therethrough whereby said tongues may be adjusted in an endwise direction.

5. A throat plate for sewing machines having a needle slot and a groove in line with said slot, a relatively thin plate fitting in said groove and projecting above the surface of the throat plate, said thin plate having a portion projecting into the needle slot and having a laterally projecting portion extending into a recess formed in the throat plate, and a clamping block secured 10 in said recess for clamping the laterally projecting portion and holding the tongue in said groove.

In testimony whereof, I affix my signature.
KARL MAIER.
